DYE JIG

Arthur E. Yates, Flintstone, Ga.

Application July 31, 1936, Serial No. 93,681

2 Claims. (Cl. 68—180)

My invention relates to an improvement in dye jigs.

- Heretofore, it has been customary to drive the so-called winding-out roll from the periphery of the machine roll in the most approved methods of dyeing cloth in dye jigs, and as the machine roll was driven at a very constant speed for dyeing, the winding out process required considerable more time than was justified.
- It is the purpose of my present invention to so locate and drive this winding-out roll that its operation is entirely independent of the speed of the periphery of the machine roll, and one object is to reduce any back lash.
- This present invention provides an entirely separate drive for the winding-out roll, so that the speed of the winding roll can be made proper and suitable for the work being done, and without any regard for the speed of cloth used in dyeing.

This invention, therefore, consists in an attachment which may be used on present dye jigs of various designs, and which will greatly reduce the time necessary to get the cloth onto and off the machine rolls.

One of the primary objects of this invention is the time saving element, meaning the provision of a construction whereby the manipulation of the cloth can be done in a small fraction of the time hitherto required.

By actual test, I have provided a machine in which the time of unwinding the cloth from the machine is reduced to about one-fourth, at the same time doing a better job with a resultant more uniform winding of the cloth on the storage roll as it leaves the machine.

As a preliminary to a fuller description of details and operation, it may be stated that cloth to be dyed usually comes wrapped around a wooden core through which a steel shaft passes so that the ends protrude beyond the rolls. When the machine is entirely free of cloth, the wooden core with the roll of dyed cloth is removed. This operation of taking the cloth off of the machine generally requires about forty-five minutes, and it is to materially reduce this time that the present invention has been made in the machine construction.

This improvement is applicable to present dye machines, or can be more advantageously incorporated into new machines.

In the accompanying drawings:

Fig. 1 is a top plan view broken out through the center;

Fig. 2 is a view in side elevation broken out through the center;

Fig. 3 is a view from one end of the machine;

Fig. 4 is a view from the opposite end of the machine;

Fig. 5 is an enlarged detail of a form of cloth winding roll showing square and central shafts, wood roll and bushings, and broken out in the center;

Fig. 6 is a side view of the chosen driving head; and

Fig. 7 is a view taken at right-angles thereto.

Referring to the drawings: This dye jig consists essentially of a dye tank or vat 1, for containing dye fluid, and in the bottom of the tank 15 or vat is a suitable drain connection 2. The tank or vat is generally enclosed within a suitable structure or frame A which latter carries the rolls and structure above the tank.

Near the bottom of the tank are two rolls 3, 20 Figs. 2, 3 and 4, the purpose of which is to guide the cloth or goods as it is passed through the dye fluid.

Above the tank are two rolls 4 and 4', upon which the cloth is wound and unwound as it passes through the dye. On one end of these rolls 4 and 4' are keyed bevel gears 5 and 5'. Bevel gears 5 and 5' mesh with bevel gears 6 and 6', Fig. 3. These gears 6 and 6' have long sleeves 7 and 7', and are fitted loosely on the drive shaft 30. However, the sleeves are fitted with friction clutches 9 and 9' so constructed that the driving hubs of the clutches are keyed to the shaft 8. A clutch shifter 10 is provided and mounted tightly on the shifter shaft 11. Depending arms 12 are mounted on shifter shaft 11, and engage up-standing levers 13. Levers 13 are keyed to the ends of two lever shafts 14, which terminate in handles 15, located within convenient reach of the operator, so that by a partial rotation of 40 either lever handle 15, the operator moves the clutch shifter and thereby engages one of the clutches and at the same time disengages the other. By engaging a clutch, he connects that clutch and gear to the drive-shaft 8, and causes 45 the roll to rotate with the shaft. Likewise, by disengaging the clutch, he disconnects the roll from the drive shaft. This action is necessary, due to the fact that the unwinding roll is revolving at continually changing revolutions per 50 minute, due to the different diameters of the cloth due to winding or unwinding on the rolls.

In Fig. 4 the cloth is shown by line 16, winding onto roll 4' from roll 4. Just as the roll 4 gets practically empty of cloth, if it is desired to pass 55

- the cloth back through the dye, the operating levers 15 are brought to central position (otherwise neutral) as shown in Figs. 3 and 4, which disengages both clutches and stops both rolls.
- 5 The cloth is now passed to the opposite side of roll 4, as shown by dotted line 17, then the operating lever is shifted in the direction of arrow D, which causes the clutch to engage and start up roll 4 in the direction of arrow B, which continues until all the cloth is wound on the roll 4. In this way the cloth can be passed back and forth through the dye as many times as necessary.

However, suppose the cloth has received sufficient dye and practically all the cloth is wound on roller 4' and it is desired to remove the cloth from the machine: In a machine fitted with this mechanism, just as the cloth is unwound from roll 4, Fig. 4, the rolls are stopped by again shifting operating levers 15 to neutral, as shown in Figs. 3 and 4, when the end of the cloth is carried up over the top roll 18, as shown by dotted line 19. Roll 18 is now started in the direction of the arrow E by shifting the lever 20, which throws clutch 21 on driving shaft 8 into engagement as shown in Fig. 4. Roll 18 continues to run at a constant number of revolutions per minute, until it has received all the cloth in the machine, after which the roll with the cloth is removed from the machine.

A desirable feature of my present invention resides in the location, construction, and method of driving this upper roll 18. It will be noted the roll is placed at a suitable location above and between rolls 4 and 4'.

Suitable bearing supports are provided for the roll. Suitable means are provided for driving the roll 18 from the drive shaft 8, and claw clutch means 21-25 is provided for disengaging said drive from the drive shaft.

The driving means above referred to for roll 18, as shown in dotted lines in Fig. 1, consists of a pair of bevel gears 22 on the shafts 35 and 36 (see Figs. 1 and 3), with belt and pulleys, or chains 23 and idler tightener 24. The clutch hub sprocket or pulley 25 (Figs. 3 and 4), is mounted loosely on drive-shaft 8, clutch member 21 is slidably keyed to drive-shaft 8, and actuated by a hand-lever 20, Figs. 3 and 4, and connected with the shifter lever 20 is pull-rod 26, terminating in an upturned handle 27, on the end of the machine opposite from the lever 20 so that the clutch 21 can be operated from either side of the machine. The members 21 and 25 of the clutch mechanism have inwardly projecting ratchet teeth, one surface of which slopes in opposite directions in said members, whereby to cause them to push apart when the speed of the top roll exceeds the speed of the drive shaft, 60 whereby said roll will finally stop without the attention of the operator.

From the foregoing description, it will be apparent that roll 18 winds up the cloth thereon with increasing speed the longer it runs, and until the completion of the winding and the roll is ready to be removed from the machine, due to the fact that the rotary motion is transmitted at the axial center of the roll instead of at the periphery. Furthermore, once the operator starts the roll 18 to remove the cloth from the tank after it has been dyed and finished, he could leave the machine by itself, and as a result of the peripheral speed of the roll itself, and in view of the direction of the teeth of the claw clutch means 21-25, the roll would have a tendency to

travel faster by momentum than the driving mechanism, and thereby automatically throw the clutch out of gear, so that the roll would come to a stop automatically.

The driving-head 28, Fig. 1, for roll 18 is shown in detail in Figs. 5, 6 and 7, and it will be noticed that there is a square counterbored hole 37 about one and one-half inches square, in the end of the head. An approved means for supporting the roll 18 is indicated in Fig. 5. This preferably consists of a square steel shaft 38 turned round for a bearing on one end 39 and left square on the other end to engage the driving-head 28 on the shaft 36 through the square hole 37.

The roll 18 is preferably in the form of a hollow wooden spool or core, as shown in Fig. 5. On this spool or core the cloth is wound. Wedge bushings 41 are provided to tighten the wood spool or core on the shaft. This complete spool or core with or without the cloth wound thereon, is removable from the machine.

This attachment is used for placing the cloth in the machine as well as removing it.

For example: A roll of cloth 30 to be dyed is brought to and placed in the machine as shown in Figs. 4 and 5, and when raised into proper position, the square end of the shaft 38 is placed in the square hole 37 in drive head 28, and the round end 39 is placed in stand-box 29. The roll 30 will then be large, full of cloth, and in the machine as shown at 30, Figs. 4 and 5. The end of the cloth is then brought down past roller 4 and on around the two rollers 3 and up to roller 4'. Roller 4' is put in operation and winds the cloth 35 upon same, see arrow C, Fig. 4.

I have shown in the foregoing how cloth can be unwound from the machine onto roll 18, as shown by dotted line 19. However, in the event cloth is wound on either of rolls 4 or 4', and it is desired to remove same from the rolls without passing it through the dye, this can be done by threading the end of cloth on either of rolls 4 or 4' up and directly upon the periphery of roll 18.

An adjustable friction band brake may be provided as shown at 31, this acting as a brake to retard the roll 18 when same is idling and unwinding the cloth onto the machine roller. It will be noted clutch 21 is disengaged and the roll is idling when the cloth is being unwound therefrom.

Similar friction band brakes may be applied to the ends of rollers 4 and 4', as illustrated by numerals 31, (Figs. 1 and 4) for retarding these rolls when they are idling.

After the cloth has been drawn back and forth through the dye as many times as required, it may be desirable to rinse out the cloth. This is done by draining out the dye through the drain 2, whereupon the vat 1 is filled and refilled with 60 fresh water and the cloth is drawn back and forth therethrough until sufficiently rinsed, after which it may be threaded into and wound over the roll 18, as hereinbefore described, completely dyed and ready for removal from the machine.

It is desirable that the rolls 4, 4' and 18 be all located over the vat, and that roll 18 is preferably located above and in the space between rolls 4 and 4' so that drainage from each roll will drop directly into the vat below.

I claim:

1. The combination of a frame, a tank having guide rollers therein, winding rolls journaled on the frame above the tank, a drive-shaft, gears for transmitting rotary motion from the drive

- shaft to the said rolls, clutch mechanism on the drive shaft, means for shifting the clutch mechanism to cause motion to be transmitted to one roll or the other, a storage roll located above the 5 drive shaft and parallel with the first-mentioned rolls, transmission means from the drive shaft to the axial center of the storage roll characterized by a shaft, gears, a pulley on said shaft and one loose on the drive shaft, a belt extending over 10 said pulleys, the hub of the pulley on the drive-shaft having claw teeth to form a clutch member, a clutch member keyed to slide on the drive shaft, and means within the control of the operator for shifting the clutch member.
- 15 2. The combination of a frame, a tank having guide rollers therein, winding rolls journaled on the frame above the tank, a drive-shaft, gears for transmitting rotary motion from the drive shaft to the said rolls, clutch mechanism on the drive 20 shaft, means for shifting the clutch mechanism to cause motion to be transmitted to one roll or the other, a storage roll located above the drive shaft and parallel with the first-mentioned rolls, transmission means from the drive shaft to the axial center of the storage roll characterized by a 5 shaft, gears, a pulley on said shaft and one loose on the drive shaft, a belt extending over said pulleys, the hub of the pulley on the drive-shaft having claw teeth to form a clutch member, a clutch member keyed to slide on the drive shaft, 10 the members of said clutch mechanism having inwardly projecting claw-teeth, one surface of which teeth slopes in a direction which will cause them to push apart when the speed of the top roll due to its momentum exceeds the speed of the 15 drive-shaft, whereby said roll will stop automatically without the attention of the operator, and means within the control of the operator for shifting the clutch member.

ARTHUR E. YATES. 20
